UNITED STATES PATENT OFFICE.

CHARLES H. BOYLE, OF NEW HAVEN, CONNECTICUT.

CORING DEVICE.

Application filed April 20, 1925. Serial No. 24,579.

This invention relates to a new and improved coring device of the type used for coring and seeding grapefruit and other fruit.

5 Among other aims and objects of the invention may be recited the provision of a device of the character mentioned, with a view to compactness, in which the number of parts are few, the construction simple, 10 the cost of production small but efficiency of operation high.

The improvements in details and arrangement of parts will be apparent from an inspection of the accompanying drawings, 15 in connection with the description hereinafter contained, wherein a preferred embodiment of the invention is disclosed for the purpose of imparting an understanding of the same.

20 In the drawings, wherein like reference characters indicate corresponding parts in the several views;

Figure 1 is a side elevation of my new and improved coring device with the members in their closed positions;

Figure 2 is an end elevation thereof;

Figure 3 is a plan view thereof;

Figure 4 is a fragmentary side elevation thereof with the members in their open positions;

Figure 5 is a side elevation of the device positioned for cutting a core of smaller size than as shown in Figure 1; and

Figure 6 is a plan view of a blank before 35 it is bent into its completed form.

My improved coring device is constructed essentially of two parts, each preferably made of a single piece of metal and pivotally connected with each other.

40 In this device I eliminate the requirement of a tubular cutter and the devices connected therewith, whereby pressure may be applied thereto in accordance with a structure now well known in the art.

45 Referring to the drawings, each of the two members 10 and 11 is preferably constructed from a single piece of sheet metal, and respectively provided with arm portions 12 and 13, which are joined at their lower ends by the semi-circular cutter portions 14 and 15. The upper free ends of the arms are joined by the rods 16 and the arms 13 are joined by an additional rod 17. These cutters 14 and 15 are preferably of such height and curvature that they will form a bowl when adjacent to each other,

as shown in Figure 4. The studs 18 provide convenient means for pivotally connecting the members 10 and 11 together.

The lower edges of the arms 13 are each provided with a stop shoulder 19, which project over and contact with the upper edge 20 of the semi-circular cutter 14 when the members 10 and 11 are in their closed position, substantially as shown in Figure 1. 60 By this engagement of the parts the cutters 14 and 15 are held in position where they combine to form substantially a complete circle and in this position they are forced downwardly into the fruit around the core 65 thereof, which is severed thereby. When the same has been pressed into the fruit a sufficient distance, the arms 12 and 13 are moved upon their pivot mounting until they occupy a position relative to each 70 other, substantially as shown in Figure 4. During this movement the cutters 14 and 15 move in a circular path around the studs 18 and the cutting edges 21 thereof pass under 75 and separate the core from the fruit upon 80 its underside.

In Figure 4 the adjacent edges 21 of the cutters 14 and 15 are indicated as being slightly separated. The relative positions of the cutters 14 and 15 are usually sufficient to separate the core from the fruit but as the cutter 15 is slightly smaller than the cutter 14, it may be moved sufficiently to pass within the latter so that the cutting edges 21 may pass each other. 90

As the coring device is lifted out of the fruit, the members are in the position substantially as shown in Figure 4, and as the core rests within the bowl formed by the inner faces of the semi-circular cutters 14 95 and 15 it is removed therewith.

In Figure 5 the device is illustrated with the arms 12 and 13 partially separated, which results in such relative positioning of the cutter portions 14 and 15 that they will cut a core much smaller than when the cutters are as arranged in Figure 1. Thus the device is not limited to successive cuttings of the same size but is adapted to cuttings of varying sizes as desired. 100 105

What I claim as new and desire to secure by Letters Patent, is:

1. A coring device including a pair of substantially similar members each having a pair of arms and a substantially semi-spherical shell-like cutter connecting the arms, said cutters being of relatively con-

- siderable width to conjointly form a bowl of substantial size when the cutting edges lie adjacent to each other so as to enable complete removal of the core by the bowl alone, and means to pivotally connect the cutters.
2. A coring device including a pair of substantially similar members each having a pair of arms and a substantially semi-spherical shell-like cutter connecting the arms, said cutters being of relatively considerable width to conjointly form a bowl of substantial size when the cutting edges lie adjacent to each other so as to enable complete removal of the core by the bowl alone, a shoulder on one member formed to engage the upper edge of the adjacent cutter so as to hold the cutting edges in substantially a common plane, and means to pivotally connect the cutters.
- 10
- 15

3. A coring device including a pair of substantially similar members each having a pair of operating arms, a substantially semi-spherical shell-like cutter connected at its free ends to the lower ends of the respective arms, means pivotally connecting the free ends of the pair of cutters, handles carried by the upper ends of the arms and being aligned with the closed ends of their respective cutters, and a stop formed on one of said arms adjacent the lower end thereof adapted to engage the upper edge of the cutter carried by the opposite arms to hold the cutting edges in substantially a common plane when said cutters are in open position.

In testimony whereof, I have hereunto af- 35
fixed my signature.

CHARLES H. BOYLE.
